UNITED STATES PATENT OFFICE.

WILLIAM ERNEST GRAY, OF BOISE, IDAHO, ASSIGNOR TO GRAY AUTOMATIC COPY INDICATOR CO., OF BOISE, IDAHO, A CORPORATION OF IDAHO.

COPY-HOLDER ATTACHMENT FOR TYPE-WRITERS.

1,209,429.

Specification of Letters Patent. Patented Dec. 19, 1916.

Application filed September 13, 1913. Serial No. 789,650.

To all whom it may concern:

Be it known that I, WILLIAM E. GRAY, a citizen of the United States, and a resident of Boise, in the county of Ada and State of Idaho, have made certain new and useful Improvements in Copy-Holder Attachments for Type-Writers, of which the following is a specification.

My invention relates to copy holder attachments for typewriters and my object is to improve such devices in a structural way, particularly a copy holder of the general type described in my Patents No. 1,183,639, granted May 16, 1916, and No. 1,144,190, granted June 22, 1915, from which it differs as to certain features, among others the particular connections adjacent the line spacing lever of the typewriter, those connections between the line indicating bar and its shifting mechanism, and the structure of the shifting mechanism itself, all as more clearly pointed out in the following description and the appended claims, constituting parts of this specification.

My device is applicable to many different kinds of typewriters, but in this instance for purposes of simplicity and convenience is shown in connection with an ordinary standard Underwood typewriter.

My invention comprehends a traveling indicator, to be mounted upon a copy board or plate, and having a general step by step motion, corresponding to line spacing, that is a step by step bodily motion downwardly, this indicator carrying a pointer and various parts coacting therewith, the pointer having a step by step horizontal motion corresponding to letter spacing. In connection with this indicator I employ a pair of flexible cables and various other parts co-acting therewith for insuring the control of the indicator from the movements of the typewriter so that the line spacer of the typewriter moves the indicator downward step by step and the keys of the typewriter or analogous letter spacing devices serve to actuate the pointer and parts immediately concerned in controlling the same.

Reference is made to the accompanying drawings forming a part of this specification in which like letters indicate like parts.

Figure 1 shows in plan a type writer and in horizontal section a copy holder board supporting the indicator mechanism, this view also showing connections from the

typewriter to the indicator, Fig. 2 is a detail view showing in perspective the line spacing lever of the typewriter and portions of my attachment immediately associated therewith, Fig. 3 is a section on the line 3—3 of Fig. 2 looking in the direction of the arrow, Fig. 4 is a section on the line 4—4 of Fig. 2 looking in the direction of the arrow, Fig. 5 is a fragmentary perspective showing a part of the mechanism for transmitting movements of the typewriter carriage to the indicator, Fig. 6 is a fragmentary section of a mechanism shown at the right of Fig. 5, and particularly the means for adjusting the tension of the chain or other flexible connection for controlling the pointer, Fig. 7 is a fragmentary perspective view of the copy holder board with my indicator mounted thereupon, Fig. 8 is a fragmentary rear view of the copy holder board and a portion of the indicator mechanism associated therewith, Fig. 9 is a view somewhat similar to Fig. 8, but with certain portions of the indicator casing removed, Fig. 10 is a view similar to Fig. 9, but with certain parts shown in Fig. 9 as removed, Fig. 11 is a section on the line 11—11 of Fig. 9 looking in the direction of the arrow, Fig. 12 is a section on the line 12—12 of Fig. 8, looking in the direction of the arrow, Fig. 13 is a perspective view of the releasing lever forming part of the indicator mechanism, and used for loosening the same relatively to the copy holder board in order to facilitate the shifting of the indicator by hand, Fig. 14 is a fragmentary perspective view showing a portion of the rack bar carried by the copy holder plate, and parts of the indicator associated therewith, Fig. 15 is a section on the line 15—15 of Fig. 7 looking in the direction of the arrow, and showing means for enabling the pointer to be shifted by hand, Fig. 16 is a detail view showing in perspective a number of parts of the indicator, Fig. 17 is a detail view showing in section a small winding drum for retracting the actuating chain used in connection with the movable pointer, and Fig. 18 is a section on the line 18—18 of Fig. 17 looking in the direction of the arrow.

A copy holder base is shown at 19 and extending upwardly from this base is a rod 20. Mounted upon this rod in any convenient manner is a copy holder plate 21. The base 19, rod 20 and plate 21, together constitute a copy holder which may be of the usual or

any desired construction. A typewriter frame is shown at 22, the platen roller at 23, the carriage at 24, and the keys at 25. The inking ribbon appears at 26 and the ribbon casings at 27 and 28, the ribbon guide appearing at 29. The platen wheel is shown at 30 and is used for turning the platen roller. The line spacing scale is shown at 31, and the adjusting lever for controlling spacing of the lines appears at 32, these parts being of the usual construction or any other construction preferred. The spacing lever of the typewriter appears at 33 and is shifted to the right according to Fig. 1, in a manner well known in this art, for the purpose of turning the platen roller 23 step by step and otherwise executing the line spacing. This lever is provided with a thumb piece 34 of the form shown more particularly in Fig. 2, and is journaled upon a pivot pin 35, the latter being carried by the typewriter carriage 24.

An arm 36 having a general arcuate form is provided at one of its ends with a wing 37 and this wing is secured to the spacing lever 33 by a bolt 38 and nut 39, the bolt 38 being curved at its inner end for the purpose of partially encircling the adjacent body portion of the spacing lever. The arm 36 is thus readily secured to the spacing lever and may be easily disconnected therefrom. The arm 36 is provided with notches 40, serving, to some extent, the purpose of graduations. Slidably mounted upon the arm 36 is a sleeve 41 having the form indicated more particularly in Figs. 2 and 4. A spring wire 42 is mounted at one of its ends upon the sleeve 41 and bent as indicated in Fig. 4. This spring wire is provided at its upper end with an eye 43 and with a portion extending through some one of the notches 40, according to the position in which the sleeve is placed relatively to the arm 36, as may be understood from Fig. 2.

The casing 41 is provided with a pair of notches 44 adapted to be brought into registry with any one of the notches 40, so that the wire 42 may, by extending through the notches 44 and some one of the notches 40, hold the sleeve 41 temporarily in a predetermined position relatively to the arm 36. The operator by shifting the sleeve 41 along the arm 36 and securing the sleeve in different positions by aid of the notch 40, as just described, can control, within reasonable limits, the distance through which the sleeve 41 travels with each movement of the spacing lever 33. The sleeve 41 is provided with a tongue 45 of sheet metal and pivotally connected with this tongue is a tubular sleeve 46, which is threaded internally. A tubular stem 47 is provided with a thread 48, which fits into the sleeve 46. The tubular stem 47 is also fitted with a sleeve 49 secured thereupon by aid of a thread 50. A metallic

wire 51 extends through the sleeve 49 and into the tubular stem 47, being secured firmly within this stem preferably by soldering.

Mounted rigidly upon the typewriter carriage 24 is a bracket 52, this bracket being detachably held in position by means of a screw 53. A tubular sheath 54 having the general form of a hollow cable is secured to the bracket 52 by aid of a sleeve 55 with which this bracket is provided for the purpose. A screw 56 extends through the wall of the sleeve 55 and grips the adjacent end of the tubular sheath. The wire 51 is both smooth and flexible and works easily in the general direction of its length within the tubular sheath.

Mounted rigidly but detachably upon the carriage 24 of the typewriter is a bracket 57 which is provided with a rearwardly extending tongue 58. Extending through a hole in this tongue is a threaded bolt 59 and fitted upon this threaded bolt is a revoluble nut 60. A fastening 61 having the form of a metallic ball is secured upon the bolt 59 by a pin 61^a, as will be understood from Fig. 6. The ball 61 is provided with an opening and a chain 62 is secured to the ball by extending into this opening and being held therein preferably by the use of solder, as may be understood from Fig. 6. The chain 62 engages a pulley 63, the latter being journaled upon a bolt 64. This bolt is carried by a bracket 65 which is mounted upon the frame work of the typewriter by aid of a bolt 66. The bracket 65 is also provided with a sleeve 67. A tubular sheath 68 similar to the sheath 64 extends into the sleeve 67 and is secured therein by aid of a screw 69. The chain 62 extends entirely through the sheath 68 and is controllable by movements of the carriage, so that as the carriage moves step by step to the left the chain is fed through the sheath 68, being drawn out of the opposite end thereof, as hereinafter described.

I will next describe the indicator mechanism, and parts associated therewith, as shown in Figs. 10 to 18 inclusive. A face plate 69 is bent substantially in U-form, as may be seen from Fig. 7, and thus provided at its top and bottom with wings 70 and 71 integral with it. These wings are provided with slots 72, and extending through these slots is a pivot pin 73. This pin is provided at one of its ends with a milled head 74 and fitted upon it at its opposite end is a milled nut 75. A hinged plate is shown at 76, and is provided with a laterally extending portion 77 of considerable length, the edges of this laterally extending portion being bent toward each other so as to form a channel 78, as will be understood from Fig. 7. The hinge plate 76 is further provided with strengthening ribs 79^a formed in it by crimping. The

hinge plate 76 is provided at its top and bottom with leaves 79 integral with it, these leaves being provided with holes through which the pivot pin 73 extends. By loosening the nut 75 the pivot pin 73 may be moved slightly along the slots 72 and the nut 75 being tightened, the pivot pin is thus located in a new position. The pivotal point of the extending portion 77 is thus rendered adjustable.

The tubular sheath 68 extends into a bearing 80 where it is rigidly held in position by a screw 81. The cable 62 after emerging from the sheath 68 and bearing 80 extends to the right according to Fig. 7 and into a casing 82 which for this purpose is provided with a hole 83. Revolubly mounted within the casing 82 is a drum 84 upon which the chain 62 is partially wound as indicated in Fig. 17. A spiral spring 85 is secured at its outer end to this drum, and at its inner end to a shaft 86, the latter being secured rigidly upon the outer end of the arm 77. The spring 85 is also under tension, and by its tendency to turn the drum 84, maintains the chain 62 likewise always under tension. A sliding plate 87 provided with a pointer 88 is mounted upon the arm 77 as indicated, and is adapted to slide thereupon in the general direction of the length of the arm. This sliding plate is bent into the form indicated in Fig. 16 and is provided with portions 89 having the form of tongues and also with an edge 90, the tongues 89 and edge 90 being so bent as to fit into the channel 78, as may be understood from Figs. 15 and 16. The sliding plate 87 is further provided with a hole 91. Extending through this hole is a threaded bolt 92, which is provided with a head 93. Encircling this bolt is a spiral spring 94. A nut 95 is fitted upon the threaded bolt 92 and engages the spring 94. The chain 62 extends through a hole 96 in the threaded bolt 92. The tension of the spring 94 by forcing the bolt 92 to the right according to Fig. 15 causes the button 93 to press the chain 62 against the adjacent portion of the sliding plate 87. This holds the sliding plate firmly upon the chain and causes it to partake of the longitudinal motion of the latter.

The operator by pressing upon the bolt 92 or upon the nut 96 can, by moving the button 93 to the left according to Fig. 15, relax the pressure normally exerted by the button 93 upon the chain and can thus loosen the sliding plate 87 relatively to the chain. By doing this the operator can shift the position of the sliding plate 87 relatively to the chain 62, and by so doing can shift the limits of travel of the pointer 88 relatively to the copy holder plate 21. Mounted rigidly upon the back of the copy holder plate 21 is a rack bar 94 provided

with teeth 95 extending parallel with the general plane of the copy holder board 21 and spaced slightly therefrom, as may be understood from Fig. 12. Two casing plates 96 and 97 are fitted together so as to form a casing, as will be understood from Figs. 8, 9 and 10. The plate 97 is provided with yokes 98 bent to engage the rack bar 94 and to partially encircle the same.

The plate 96 is provided with a flange 99 which is bent to fit the adjacent surface of the rack bar 94. The flange 99 is provided with a projecting tongue 100 which fits into a mating notch 101 with which the plate 97 is provided. The purpose of this arrangement of the plates 96 and 97 is to form a casing without the aid of screws. The plate 96 is provided with a slot 102 to facilitate the working of certain parts. Extending through the casing is a shaft 103 and mounted rigidly upon this shaft is a gear wheel 104, the teeth of which mesh with the teeth 95 of the rack bar 94. A ratchet wheel 105 is also mounted rigidly upon the shaft 103. A yoke 106 having the form indicated in Fig. 13, is provided with a hole 107 through which the shaft 103 extends. This yoke carries a pin 108, and journaled upon the latter is a lever 109. This lever carries a tooth 110 integral with it and adapted to engage the teeth of the ratchet wheel 105. The yoke 106 is provided with a lug 111 integral with it and extending over the lever 109 so as to serve as a limiting stop therefor. A spring 112 made of a single piece of wire is mounted upon the yoke 106 by aid of a screw 113; this spring engaging one edge of the yoke and also engaging the lever 109. The wire 51 after emerging from the sheath 54 is secured to a fastening 114 carried by the yoke 106. A wire spring 115 (see Fig. 8) is secured in position by a screw 116 and engages the lower edge of the plate 96. The upper end of this wire spring bears against the screw 108 and thus tends to maintain the yoke 106 in its extreme position to the left according to Figs. 8 and 9. The tension of the spring 115 by its effect upon the yoke 106, as just stated, causes the wire 51 to be normally drawn tight—that is, the wire is always under tension.

The operator by raising the outer or free end of the lever 109 can disengage the tooth 110 from the ratchet wheel 105, as indicated in Fig. 10, and this being done the casing and parts carried by it may slide either up or down as desired and thus adjusted in any vertical position within the limits of its travel. Each time the wire 51 is drawn to the right according to Fig. 8, the yoke 106 is rocked slightly in a clock-wise direction, the lever 109 is actuated in the same direction, and the tooth 110 carried by the lever 109 is brought into engagement with the

- ratchet wheel 105 so as to turn the latter in a clock-wise direction according to Fig. 10, to a distance representing the distance apart of two consecutive teeth of the toothed wheel 104. A pawl 117 is mounted upon a bolt 118 and is provided with a tooth 119 for engaging the teeth of the wheel 104. This pawl is engaged by a spring 120, the latter being secured upon a bolt 121, as may be understood from Fig. 10. A sheet of copy is shown at 122 and is mounted upon the copy holder plate 121 in any approved manner.

The operation of my device is as follows: The parts being assembled and arranged, as above indicated, the operator shifts the sleeve 41 upon the arm 36 into any one of a number of predetermined positions associated with the notches 40, the position selected being dependent upon the length of the line spacing desired for the indicator to follow upon the copying plate 21, that is to say, the line spacing to be indicated upon the copy is made single, double, triple, etc., according to the manner in which the copy was originally prepared. If the line spacing of the copy is very wide the sleeve 41 is shifted correspondingly further to the left according to Fig. 2. The lever 109 is now raised, and the casing of the indicator is slid up or down along the rack bar 94 until the arm 77 is brought into proper registry with the first line of the copy.

If it be desired to have the pointer 88 follow the copy letter by letter, as indicated in Fig. 7, the pointer 88 is brought directly below the first letter or other character to be copied. The plate 87 is adjusted relatively to the chain 62, if any adjustment be needed.

For this purpose the operator presses upon the bolt 92 or upon the nut 95 (see Fig. 15) so as to loosen the chain 62 and then by moving the plate 87 to the right or left the pointer 88 is brought into proper registry. If further adjustment of the cable 62 be desired it can be accomplished by shifting the position of the bolt 59, this being done by simply turning the nut 60 (see Fig. 6) as elsewhere explained. These steps being performed the pointer 88 indicates not only the first line of the copy, but also the first letter of the line to be copied. The typewriting machine is next operated in the usual manner. Each time a key 25 is depressed so

that the carriage of the typewriter moves to the left according to Fig. 1, to an extent representing the space between two consecutive letters being copied, the chain 62 is fed into the tubular sheath 68, the tension of the chain being taken up at the opposite end of the chain by the winding drum 84, as above explained, this drum being turned by the spring 85. The line being finished the operator shifts the line spacing lever 33 to the right according to Fig. 1. This causes the arm 36 to swing and the wire 51 is pulled to

the left according to Fig. 1 and then relaxed. The wire at its other end (see Fig. 8) thus pulls upon the bolt 114 and causes the yoke 106 to rock in a clock-wise direction according to Figs. 8, 9 and 10, so that the ratchet wheel 105 is turned one step in a clock-wise direction, as indicated by the arrow in Fig. 10. This causes the toothed wheel 104 to turn to a sufficient extent to lower the casing relatively to the rack bar 94. The arm 77 is thus lowered so as to bring the pointer 88 into registry with the next line. Each time the carriage of the typewriter reaches the limit of its travel to the left and is brought back, in the conventional manner, to its starting point, the corresponding movement of the chain 62 causes the plate 81 and pointer 88, together with the mechanical parts carried by the plate 81, to be shifted to the left according to Fig. 7, so as to be in position to start indicating the letters of a new line.

It will be noted that while the line spacing of the typewriter may, by the lever 32, be gaged within conventional limits this gaging is independent of the line spacing of the attachment for the copy holder which is controlled, as above explained, by the position of the sleeve 41. Such being the case the line spacing of the typewriter may be single, double or triple and the line spacing of the copy holder may be the same as that of the typewriter, or may be different from it as desired. For instance the typewriter may be adjusted for double spacing and the typewriter attachment for the copy holder may be adjusted for either single spacing or double spacing.

While I show the parts mounted as here indicated I do not limit myself to this precise arrangement, neither do I limit myself to the exact details of construction shown, as variations may be made without departing from the spirit of my invention, the scope of which is commensurate with my claims.

I claim:—

1. In a copy holder attachment for typewriters, the combination with the line spacing lever of a typewriter having a vertical pivot bolt, of an arcuate arm having a plurality of notches and engaging the pivot bolt at one end and having a wing projecting along the lever, a hook bolt connecting the wing with the lever, a clip adjustable on the said arm, a spring wire secured to and carried by the clip and engageable within a selected notch of the arm to hold the clip in desired position, a copy holder plate, an indicating bar movable thereon, mechanism for shifting said bar with respect to the said plate, and flexible means connecting said clip with the said shifting mechanism whereby to actuate the latter when the line spacing lever is moved.

2. In a copy holder attachment for typewriters, the combination with the line spacing lever of a typewriter having a vertical pivot bolt, of an arcuate arm having a plurality of notches and having a wing extending along and bolted to the said lever, a clip adjustable on said arm, a spring wire carried by the clip and engageable within a selected notch of the arm to hold the clip in desired position, a copy holder plate, an indicating bar movable thereon, mechanism for shifting said bar with respect to the plate, and flexible means connecting said clip with the said shifting mechanism whereby to actuate the latter when the line spacing lever is moved.
3. In a copy holder attachment for typewriters, the combination with the line spacing lever of a typewriter, of an arcuate arm having a plurality of notches and provided with an extension secured to the lever, a clip adjustable on said arm and having means engageable within a selected notch of the arm in order to hold the clip in desired position, a copy holder plate, an indicating bar movable thereon, mechanism for shifting said bar with respect to the plate, and flexible means connecting said clip with the said shifting mechanism whereby to actuate the latter when the line spacing lever is moved.
4. In a copy holder attachment for typewriters, the combination with the line spacing mechanism of a typewriter of a copy holder plate, a rack bar mounted upon the plate, an indicating bar extending across the plate, mechanism for adjusting the indicating bar on the plate actuated from said line spacing mechanism and including a casing slidably disposed upon one edge of the plate, a shaft mounted in the casing, a gear wheel mounted on the shaft and engaging the rack bar, a ratchet wheel rigid with the said gear wheel, a yoke journaled on the shaft and provided with a laterally projecting lug, a lever pivoted at its inner end upon the yoke and having its outer end extending exteriorly of the casing, said lever being provided with an intermediate tooth constituting a pawl and in engagement with the ratchet wheel, and a flexible connection attached to the said line spacing mechanism and secured to the yoke for actuating the same, said lever having a limited movement

between the ratchet wheel and the said lug of the yoke in order to disengage the same from the ratchet wheel and permit of sliding movement of the casing independent of the said flexible connection.

5. In a copy holder attachment for typewriters, the combination with the line spacing a mechanism of a typewriter of a copy holding plate, a rack bar carried by the plate, an indicating bar extending across the plate, mechanism for adjusting the indicating bar with respect to the said plate actuated from said line spacing mechanism and including a casing having sliding movement along one side of the plate, a shaft mounted in the casing, a gear wheel mounted on the shaft and in engagement with the said rack bar, a ratchet wheel rigid with the gear wheel, a yoke journaled on the shaft, a lever pivoted on the yoke and having an intermediate tooth movable into and out of engagement with the ratchet wheel, a spring carried by the yoke and engaging the lever to normally hold the latter in engagement with the ratchet wheel, and a flexible connection from the said yoke to the line spacing lever of a typewriter.

6. In a copy holder attachment for typewriters, the combination with the line spacing mechanism of a typewriter of a copy holder plate, a rack bar mounted upon said plate, an indicating bar extending across the plate, mechanism for shifting the indicating bar on the plate actuated from said line spacing mechanism and including a casing comprising a pair of plates bent along one edge to slidably embrace the rack bar and having relatively engageable lugs and recesses to support the same in connection with one another, a shaft extending from one of the plates, a gear wheel mounted on the shaft and in engagement with the rack bar, a ratchet wheel rigid with the gear wheel, and a yoke journaled on the shaft and having a spring controlled pawl engageable with and disengageable from the said ratchet wheel, and a flexible connection from the said yoke to the line spacing lever of a typewriter.

WILLIAM ERNEST GRAY.
